US00D864161S

(12) **United States Design Patent** (10) **Patent No.:** **US D864,161 S**
(45) **Date of Patent:** **** Oct. 22, 2019**

(54) **WIRELESS SPEAKER**

- (71) Applicant: **Ring Inc.**, Santa Monica, CA (US)
- (72) Inventors: **John Modestine**, Los Angeles, CA (US); **Mark Siminoff**, Mountain View, CA (US); **Christopher Loew**, Palo Alto, CA (US)
- (73) Assignee: **Amazon Technologies, Inc.**, Seattle, WA (US)
- (**) Term: **15 Years**
- (21) Appl. No.: **29/633,855**
- (22) Filed: **Jan. 16, 2018**

Related U.S. Application Data

- (63) Continuation of application No. 29/571,957, filed on Jul. 22, 2016, now Pat. No. Des. 812,590.

CLAIM

The ornamental design for a wireless speaker, as shown and described.

DESCRIPTION

FIG. 1 is a front perspective view of the wireless speaker according to the present design;

FIG. 2 is a front elevational view of the wireless speaker of FIG. 1;

FIG. 3 is a rear elevational view of the wireless speaker of FIG. 1;

FIG. 4 is a right-side elevational view of the wireless speaker of FIG. 1;

FIG. 5 is a left-side elevational view of the wireless speaker of FIG. 1;

FIG. 6 is a top plan view of the wireless speaker of FIG. 1; and,

FIG. 7 is a bottom plan view of the wireless speaker of FIG. 1.

Broken lines, where used, are for illustrative purposes only and form no part of the claimed design.

1 Claim, 7 Drawing Sheets
